(57) CLAIM

The ornamental design for a game machine storage bag as shown and described.

DESCRIPTION

1. Game machine storage bag

1.1 : Perspective

1.2 : Front

1.3: Back

1.4 : Left

1.5: Right

1.6:Top

1.7: Bottom

FIG.1.1 is a perspective view of a game machine storage bag according to a first embodiment showing my new design; FIG.1.2 is a front view thereof; FIG.1.3 is a rear view thereof; FIG.1.4 is a left side view thereof; FIG.1.5 is a right side view thereof; FIG.1.6 is a top view thereof; FIG.1.7 is a bottom view thereof.

The broken lines shown throughout the reproductions illustrate portions of the game machine storage bag that form no part of the claimed design.

1 Claim, 7 Drawing Sheets
